FRANK M. ALLEN, OF CLAYMONT, DELAWARE, ASSIGNOR TO CONGOLEUM-NAIRN, INC.,
A CORPORATION OF NEW YORK

METHOD OF PRINTING

Application filed December 7, 1927. Serial No. 238,259.

The invention relates to printing machines, and more particularly to printing machines of the bed-and-platen type as described and claimed in the Waldron Patent No. 1,145,821.

Printing machines of the type referred to, comprise, in general, a set of platens carrying printing blocks, which are adapted to be reciprocated by suitable mechanism to impress a design upon a base material as it is conveyed 10 step by step through the machine over the bed and work-supporting members. In the present-day machines, the work-supporting members consist of flat pads each having a wood backing and a top of wool felt of uniform thickness, covered with oilcloth or similar material. The pads are suitably cradled in the framework of the print machine beneath the set of platens, the felt faces being adapted to provide flat, compressible work- 20 supporting surfaces, against which the print blocks may abut without injury to their printing surfaces. Intermediate the work-supporting members or pads, and in a plane therewith, are wood or steel plates, forming 25 with said pads a continuous flat bed over which the work is conveyed. As the flat print block is brought into association with the work supported by the flat felt pad for the purpose of depositing paint thereon, or for flattening or "mashing" the paint previously deposited, a strong cohesive relation is set up 30 between the print block and the work, whereby the raising of the print block from the printed surface is opposed with great resistance. In consequence, the work is slightly raised from the work-supporting member by the suction of the block, until the opposing forces break the bond and the work is suddenly torn from the block. Frequently, this 35 results in spattering the paint and in many instances the paint is raised in pits and points so that the work has an uneven and rough appearance. With relatively slow reciproca- 40 tion of the platens and blocks, this defect, 45 while apparent, is not serious, but as the speed

of operation is increased, the defect becomes most serious, and functions as one of the chief factors in limiting the printing capacity of the machine.

The chief object of my invention is the provision of a novel method for reciprocating the platens carrying the print blocks, whereby the defects outlined above are substantially eliminated and an increased speed of operation is obtained. 50

In the accompanying drawing, forming a part of this specification: 55

Figure 1 represents a sectional elevation of the conventional bed-and-platen type printing machine, adapted to operate in accordance with my invention. 60

Figure 2 is a graphical representation of the novel mode of reciprocation of the platens. 65

Referring to the drawings, 1 designates the framework of a bed-and-platen type printing machine. Cradled in the framework or the work-supporting members constituting the bed 2 over which the work is conveyed step by step by the endless pick belts 3. Mounted over the work-supporting members are platens 4 carrying the print blocks 5. The platens are supported at each end by the vertical members, 6, 6', which are slidably journaled in the bearings 7, 7', and 70 are adapted to be reciprocated by means of the cams 8, 8' and the cam followers 9, 9'. The cams 8, 8' are keyed to the driving shaft 10, which is suitably journaled in the framework 75 1. 80

In the construction and operation of the present-day bed-and-platen type machines, the cams 8, 8' are symmetrically designed and are so positioned upon the shaft 10 as to cause the cam followers 9, 9' to move simultaneously and co-extensively. Thus, the platens 4 and blocks 5, when once adjusted to the position parallel to the print bed 2, remain in such parallel relation throughout the complete cycle of vertical reciprocation. 85 90

In contradistinction to this mode of operation, the present invention contemplates that the platens and blocks shall move in parallel alignment with the print bed throughout a portion only of the cycle of operation, and during the remaining portion of the cycle shall assume an oblique alignment for the purposes hereinafter explained. More particularly, the print block is first positioned in parallel alignment with the bed at substantially the full height of its vertical movement. While thus positioned, the print carriage (not shown) passes therebeneath in the usual manner to deposit the coloring matter upon the printing surface of the block. The platen or block then moves vertically downward into printing position, while constantly maintaining the parallel alignment. At the end of the printing period, one end of the platen or block is raised a substantial amount, while the opposite end is still maintained in printing position. By this movement, the parallel alignment of the print block and bed is destroyed and the block is separated from the imprinted surface by line-contact disengagement. Both ends of the block are then moved vertically upward, the lower end being raised more rapidly, whereby the block and platen having reached their full upward vertical movement, are restored again to parallel alignment.

As a simple and preferred manner of carrying out my invention, I construct the platen cams 8, 8' so that when the cams are properly positioned upon the shaft 10 to cause parallel alignment of the bed and platens during the vertical downward movement and printing period, the lifting sector of cam 8 becomes effective prior to the lifting sector 40 of cam 8'. In this manner, one end of the platen is raised the desired amount, while the opposite end remains in printing position. The remaining portion of the lifting sector of the cams will be of such design as 45 to cause the platen to return to parallel alignment with the bed before or upon reaching its full vertical upward movement.

In Figure 2, I have illustrated graphically the movement of the platen or block throughout the cycle of operation, curves A and B defining the movement of the ends of the block indicated by *a* and *b* respectively. From *r* to *s*, both ends *a* and *b* of the block move downward simultaneously and co-extensively as indicated by the coincidence of curves A and B. During the period *s* to *t*, the print block is in printing position and in parallel alignment with the print bed. At *t*, the end of the block *a* commences its upward vertical movement as indicated by the curve A, while the end of the block *b* remains in printing position as indicated by the portion *t* to *u* of the curve B. This angular movement of the block causes the same 65 to separate from the imprinted surface by

line-contact disengagement in contradistinction to the plane-cleavage disengagement as in the heretofore known manner of operation. At the points *p* and *u*, the print block has assumed an oblique alignment substantially as shown in the dotted lines in Figure 1. In most cases, this vertical movement of one end of the print block will be about 1" for standard blocks of 72" length. With longer blocks i. e., wider print machines, the movement may be somewhat greater. In general, however, it may be stated that for bed-and-platen type print machines of the Waldron type, the safe permissible angle between the block and bed, is about one degree. This angle is, however, ample for securing the advantages of line-contact disengagement and also permits the highly desirable rigid construction of the print machine to be maintained. The block having been substantially separated from the imprinted surface, both ends thereof then move upward from the points *p* and *u* as indicated by the independent curves A and B, until the block returns to parallel alignment as indicated at *v*. Such parallel alignment continues until the block has again reached the point *t* in the subsequent cycle of operation.

By means of my invention, the print block is brought into printing position in parallel alignment with the bed, thereby providing a uniform print upon the work. As the block commences its upward movement subsequent to the printing period, however, the parallel alignment is destroyed, thereby causing the work to separate from the printing surface, commencing at one end of the block, smoothly and easily by line-contact disengagement. This feature of line-contact disengagement, similar to the "peeling" action in rotary printing machines, entirely avoids the sudden plane-cleavage of the bond between the print block and the work. Furthermore, such operation substantially eliminates all spattering occurring from the sudden separation of the print block and work, and avoids the formation of pits and points of paint. Of chief importance, however, is the fact that by the application of the principle of my invention, I am able to obtain a considerably increased speed of reciprocation of the print blocks, which results in increased capacity of the print machine, and at the same time to produce prints which have a uniform and smooth finish.

I claim:

1. In the operation of a bed-and-platen type printing machine of the type described, the steps of first effecting plane-contact engagement of the print block and surface to be printed, and finally effecting line-contact disengagement of the print block and imprinted surface said disengagement commencing at the one end of the print block

and extending to the opposite end of the print block.

2. In the operation of a bed-and-platen type printing machine of the type described, maintaining parallel alignment of block and bed during the vertical downward movement of the platen and the printing period, destroying the parallel alignment just subsequent to the printing period to cause line-contact disengagement of the block, and finally restoring the parallel alignment before the completion of the upward vertical movement of the platen.

In testimony whereof, I affix my signature.

FRANK M. ALLEN.
